UNITED STATES PATENT OFFICE.

FRANK J. BECKER, OF INDEPENDENCE, MISSOURI.

DOOR-SUPPORT.

1,102,855.

Specification of Letters Patent.

Patented July 7, 1914.

Application filed March 18, 1914. Serial No. 825,569.

To all whom it may concern:

Be it known that I, FRANK J. BECKER, a citizen of the United States, residing at Independence, in the county of Jackson and 5 State of Missouri, have invented new and useful Improvements in Door-Supports, of which the following is a specification.

This invention is an improved door support for use on a door to prevent the same 10 from sagging, the object of the invention being to provide an improved device of this character which is cheap and simple, the parts of which may be readily attached to a door and to a door jamb, which is incon- 15 spicuous, is not likely to get out of order and which effectually prevents a door from sagging.

The invention consists in the construction and combination and arrangement of de- 20 vices hereinafter described and claimed.

In the accompanying drawing:—Figure 1 is a perspective view of a portion of a door and of a jamb, provided with door supporting means constructed in accordance with 25 my invention, the door being shown partly open. Fig. 2 is a horizontal sectional view of the same with the door closed. Fig. 3 is a vertical section on the plane indicated by the line *a—a* of Fig. 2. Fig. 4 is a similar 80 view on the plane indicated by the line *b—b* of Fig. 3.

For the purposes of this specification a door is indicated at 1 and the jamb of the door frame, against which the door closes, is indicated at 2. In accordance with my invention I provide an improved keeper plate 3 which is adapted to be rabbeted in the door jamb to lie flush with the surface thereof, and this keeper plate is provided at its 40 upper end with an outwardly extending arm 4, the upper side of which is inclined to form a cam as at 5. An auxiliary keeper plate 6 is provided which is rabbeted and secured to the jamb at a suitable distance 45 above the keeper plate 3. A casing 7 is adapted to be mortised in the door at the free edge thereof, on one side and at a point opposite the keeper plate, this casing having a face wall 8 which extends across and 50 is rabbeted in the edge of the door and also having a side wall 9 which is rabbeted in one side of the door and is provided with a longitudinal slot 10. The casing is provided with a longitudinal cylindrical bore which 55 opens through the face plate. A bolt 11 is arranged in this bore for longitudinal move-

ment and is formed with a reduced spindle 12 for the greater portion of its length, on which spindle is mounted a sleeve roller 13 for revolution, a washer 14 being secured 60 on the outer end of the spindle as by means of a pin 15 and serving to keep the roller in place on the spindle of the bolt. A knob or head 16 is provided with a stud 17 which has threaded engagement with a transverse 65 opening in the bolt and operates in the slot 10 of the side wall 9. This head projects beyond the side wall 9 and enables the bolt to be adjusted so as to project the sleeve roller to any required distance beyond the 70 face wall, according to the width of the crack between the free edge of the door and the jamb when the door is closed.

In the operation of my improved door support the sleeve roller on the bolt en- 75 gages the cam 5 of the keeper plate as the door nears a closed position and moves upwardly on said cam face as the door closes, thereby causing the bolt to lift the free side of the door, and as the said bolt bears on 80 the upper end of the keeper plate when the door is closed said keeper plate and bolt coat with each other to support the free side of the door and effectually prevent the same from sagging. The bolt when adjusted 85 is secured in adjusted position by tightening the screw stem of the knob or head so as to clamp the latter to the outer side of the side wall 9. The bolt once properly adjusted remains in such adjusted position unless 90 the door or frame should swell or expand, in which event the bolt should be re-adjusted according to the width of the crack.

While I have herein described and shown a preferred form of my invention I would 95 have it understood that changes may be made in the form, proportion and construction of the several parts without departing from the spirit of the invention and within the scope of the appended claims.

Having thus described my invention, I 100 claim:—

1. The hereindescribed door support comprising a keeper for attachment to a jamb and having an inclined cam surface to project beyond one side of the jamb, in combination with a frame for attachment to the free side of the door and a bolt projecting from said frame to engage and ride up on the cam of the keeper when the door closes 105 and thereby raise and support the free side of the door, and means to adjust said bolt 110

in the frame so that it may be caused to project to any desired extent from the free side of the door.

2. The herein described door support comprising a keeper for attachment to a jamb and having an inclined cam surface to project beyond one side of the jamb, in combination with a frame for attachment to the free side of the door and a bolt projecting from said frame to engage and ride up on the cam of the keeper when the door closes and thereby raise and support the free side of the door, and means to adjust said bolt in the frame so that it may be caused to project to any desired extent from the free side of the door, and a sleeve roller on the said bolt and adjustable therewith in the said frame.

3. The herein described door support comprising a keeper for attachment to a jamb and having an inclined cam surface to pro-

ject beyond one side of the jamb, in combination with a frame for attachment to the free side of the door and provided with a guide bore and also with a side wall having a longitudinal slot, a bolt arranged in said bore means to adjust said bolt in the bore to cause the outer end of the bolt to project beyond the face end of the frame, a sleeve roller on the outer end of the said bolt and adjustable therewith in said bore and an operating and securing head bearing on the outer side of said frame and movable thereon, said head having a threaded stud engaging a transverse threaded opening in the bolt.

In testimony whereof I affix my signature in presence of two witnesses.

FRANK J. BECKER.
